United States Patent Office

Des. 225,154
Patented Nov. 21, 1972

225,154

BOTTLE OR SIMILAR ARTICLE

Monroe J. Singer, 3160 NW. 80th Terrace,
Miami, Fla. 33147

Filed July 6, 1971, Ser. No. 160,272

Term of patent 14 years

Int. Cl. D9—01

U.S. Cl. D9—48

FIG. 3

FIG. 1

FIG. 2

FIG. 4

FIG. 1 is an elevational view of a bottle or similar article showing my new design;

FIG. 2 is an elevational view looking from the right of FIG. 1;

FIG. 3 is a top plan view; and

FIG. 4 is a bottom plan view thereof.

I claim:

The ornamental design for a bottle or similar article, substantially as shown.
